UNITED STATES PATENT OFFICE.

ALBERT W. ADCOCK, OF CHICAGO, ILLINOIS.

DESIGN FOR A BADGE.

SPECIFICATION forming part of Design No. 33,276, dated October 2, 1900.

Application filed August 17, 1900. Serial No. 27,218. Term of patent 14 years.

To all whom it may concern:

Be it known that I, ALBERT W. ADCOCK, a citizen of the United States, residing at Chicago, in the county of Cook and State of Illinois, have invented and produced a new and original Design for a Badge, of which the following is a specification, reference being had to the accompanying drawing, forming part thereof.

10 The figure is a front view of the badge, showing my new design.

As illustrated in the drawing, my design consists of a modified Maltese cross, the arms 1 thereof radiating from a circular center 15 piece, consisting of a rosette 2, inclosed by an annular band 3, which forms a border therefor. The intermediate portion of the end of each arm 1 of the cross is cut away, making the arms two-pointed, and each arm is provided with a border, consisting of a band 5, which extends from the annular band 3 along and around the margin of the arm back to the band 3, forming a V-shaped field 6 be-

tween the outer margin of the band 3 and the inner margin of the band 5. The cross is ²⁵ can-
toned with rays 4, which substantially conform in outline to the outline of the arms of the cross, so that the whole forms a cross of eight points.

The rosette 2, located at the center of the ³⁰ badge and constituting the leading feature of my design, is divided into eight triangular parts, having their sides bounded by compound curved lines emanating from a point at the center of the rosette and extending ³⁵ substantially radially to the band 3.

Having described my invention, what I claim as new, and desire to secure by Letters Patent, is—

The design for a badge, substantially as ⁴⁰ herein shown and described.

ALBERT W. ADCOCK.
